No. 830,408.

PATENTED SEPT. 4, 1906.

W. S. & H. H. BREEDEN.
DEVICE FOR MAKING AND FINISHING BOTTLE NECKS.
APPLICATION FILED OCT. 11, 1905.

UNITED STATES PATENT OFFICE

WILLIAM SHEPARD BREEDEN AND HOWARD HANN BREEDEN, OF
BRADFORD, PENNSYLVANIA.

DEVICE FOR MAKING AND FINISHING BOTTLE-NECKS.

No. 830,408.

Specification of Letters Patent.

Patented Sept. 4, 1906.

Application filed October 11, 1905. Serial No. 282,257.

To all whom it may concern:

Be it known that we, WILLIAM SHEPARD BREEDEN and HOWARD HANN BREEDEN, citizens of the United States, and residents 5 of Bradford, in the county of McKean and State of Pennsylvania, have invented a new and Improved Device for Making and Finishing Bottle-Necks, of which the following is a full, clear, and exact description.

10 Our invention relates to a machine for making and finishing the necks of glass-blown jars, bottles, and homeopathic vials; and the purpose of the invention is to provide a machine in which a revoluble shaping 15 and polishing tool is employed for that portion of the tube to be formed into the neck of a bottle, jar, or vial, and means for adjusting the bottle to the said tool, and also means for bringing the tool quickly into and out of 20 action with relation to the neck of the bottle.

A further purpose of the invention is to provide a machine of the character mentioned which will comprise but few parts and which is simple and durable in construction 25 and effective in operation, the machine being fully under the control of one individual.

The invention consists in the novel construction and combination of the several parts, as will be hereinafter fully set forth, 30 and pointed out in the claims.

Reference is to be had to the accompanying drawings, forming a part of this specification, in which similar characters of reference indicate corresponding parts in all the 35 figures.

Figure 1 is a side elevation of the machine, parts being broken away. Fig. 2 is a horizontal section taken practically on the line 2 2 of Fig. 1. Fig. 3 is a horizontal section 40 taken substantially on the line 3 3 of Fig. 1, and Fig. 4 is a detail perspective view of one of the jaws for forming the neck of the bottle or vial.

A represents a portion of a table or a bench, 45 and B the base of the machine, which is secured to the table or bench in any approved manner, and said base B is provided with a central aperture, surrounded by a collar 10, extending both above and below the base and 50 through an opening in the said table, which collar 10 serves as a bearing for the lower end of a vertical shaft C. At one corner portion of the base B another aperture is made, surrounded by an upwardly-extending guide-

collar 11, and a corresponding aperture is 55 preferably produced in the table or bench A. The guide-collar 11 receives the lower end of a supporting-rod 12, and said rod has play in the said collar 11 and may be of any desired height, being provided at its upper end with 60 an inwardly-extending horizontal portion 12^a, and said rod 12 is adjustably secured in the said guide-collar 11 by means of a set-screw 13 or its equivalent.

Adjacent to the upper end of the shaft C a 65 collar 14 is produced, which is preferably polygonal in general contour, and from the central portion of the upper end of the said shaft C where the collar 14 is located an upwardly-extending shaping-plug 15 is produced, 70 adapted to enter the neck of the bottle and shape the same as the shaft C is revolved, the upper face of the mouth portion of the bottle resting at the same time upon the upper face of the collar 14, so that the 75 said collar tends to shape the said upper portion of the neck of the bottle at its mouth, as is clearly shown in Fig. 1, the bottle being designated as 22. A block 16 is secured to the said shaft C a desired distance from the 80 forming or shaping plug 15, the attachment being made through the medium of a set-screw 16^a, for example, and, as is particularly illustrated in Fig. 2, this block 16 is provided with vertical recesses or slots 17 in 85 its side edges, and these slots have usually a tapering inner wall and are widest at their lower ends.

In connection with the block 16, carried by the shaft C, shaping-jaws D are employed, 90 adapted to face one another, and each shaping-jaw is provided with a fin 18, longitudinally produced on its inner face at its lower portion. The fins of the said jaws D are made to enter the slots or recesses 17 and are 95 pivoted therein by pins 19, passed through the fins 18 about centrally between the ends of the fins and through the lower corner portions of the slotted side sections of the block 16, as is shown in Figs. 1 and 2. The inner 100 side edges of the fins 18 are beveled in direction of their ends in opposite directions from a central point, as is best shown in Fig. 4, and the apertures through which the pins 19 pass are produced in the said fins 18 adjacent to 105 the said central portion of the said inner edges.

Each jaw D is provided with a head 20 at

its upper end, and each head at its inner face is provided with two stepped projections—namely, an upper projection 20^a and a lower projection 20^b, immediately following the upper one, the upper projections 20^a of the said jaws being made to extend farther inward than the lower stepped projections 20^b, as is best shown in Fig. 1. As the shaft C is revolved the upper stepped projections 20^a are brought into proper engagement with the outer face of the bottle-neck just below the mouth, as is shown by full lines in Fig. 1, so as to form or shape the neck properly at such point; but normally the upper ends of the said jaws D are made sufficiently heavy to cause the said jaws to swing outward in opposite directions, swinging on their pivots 19, as is shown by dotted lines in Fig. 1, in which position the heads of the jaws clear the neck portion of the bottle 22.

In operation the bottle 22 is placed mouth down in the machine, and the body of the bottle is supported by a guide-head E. This guide-head is provided with upper and lower horizontal jaws 21, the jaws at the top and bottom being in pairs, and the space between the jaws of a pair is V-shaped, as is clearly shown in Fig. 3. This head is supported on the horizontal arm or member 12^a of the supporting-rod 12, as is best shown in Fig. 3, the said arm or member 12^a being passed through a suitable aperture 23, adjacent to one side of the said guide-head, and the head is held in adjustable position on the said member 12^a by a set-screw 24 or its equivalent.

By reason of the adjustment of the supporting-rod 12 in the base of the machine and the adjustment of the guide-head E on said supporting-bar various-sized vials or bottles may be accommodated and successfully shaped and made on the machine.

The head portions 20 of the jaws D are brought together when desired to shape the bottle-neck by forcing a cone 25 upwardly between the lower inclined edges of the fins 18 of the said jaws D, at which time the lower ends of the jaws are forced apart and their upper ends are consequently brought in direction of each other until stopped by the engagement of the lower stepped projections 20^b with the shaping-collar 14.

A spring 26 is coiled around the shaft between the cone 25 and the block 16, on which the jaws D are pivoted, and the said cone, which is mounted to slide upon yet turn with the shaft C, is provided with an annular groove 27, which receives projections from the spanner-arm 26^a of a hand-lever 28, fulcrumed upon a suitable support 29, located on the base-plate B, preferably adjacent to the guide-collar 11, as is best shown in Fig. 2.

The shaft C is revolved by carrying a belt from any source of power over a pulley 30,

located, preferably, at the lower end of the 65 shaft, as is clearly illustrated in Fig. 1.

This machine is exceedingly simple, it is durable, and will effectually shape the neck and mouth of any form of bottle, vial, or jar made of blown glass, it being understood that 70 the glass is operated upon while hot.

Having thus described our invention, we claim as new and desire to secure by Letters Patent—

1. In a machine for making and shaping 75 the necks of glass bottles, vials, &c., an adjustable holder for the article, a shaft mounted to rotate, means for driving the same, a forming-plug carried by the shaft for application to the interior of the article to be operated upon, external shaping-jaws capable of movement toward and from each other, the jaws being provided with longitudinal fins having beveled surfaces, a block secured to said shaft upon which the jaws are pivoted, 85 means for controlling the movement of the jaws and comprising a member movable on the said shaft adjacent to the block, and a spring on the shaft between said movable member and the said block.

2. In a machine for making and shaping the necks of glass bottles, vials, &c., a holder for the article, a shaft mounted to rotate, a forming-plug carried by the shaft and adapted to enter the neck portion of the article, a 95 block carried by the shaft and having slots in its side edges, jaws having shaping-heads for engagement with the outer face of the neck of the article, to shape the same, each jaw being provided on its inner face at the lower 100 portion with a longitudinal fin, the inner side edges of the fins being beveled in opposite directions from the center, the said fins being pivoted at their central portion in the slots in the sides of the block, and means for engaging the beveled edges of the fins to control the movement of said jaws.

3. In a machine for making and shaping the necks of glass bottles, vials, &c., a base, a collar fitting an aperture in the base, a vertical shaft mounted at its lower end in the collar, and extending below the base, the shaft being provided at its lower end with a pulley, a collar at the upper end of the shaft, a forming-plug extending upward from the collar, a 110 block adjustably secured to the shaft, shaping-jaws pivoted at opposite sides of the said block, and having heads at their upper ends provided upon their inner faces with shaping members, the said heads being at opposite 115 sides of the forming-plug and collar, a cone revolvably and slidably mounted on the shaft below the said block and engaging beveled surfaces on the jaws to force the heads of the jaws in direction of each other, a coiled 120 spring on the said shaft between the cone and the block, an operating device for said cone, a guide-head for the article to be oper- 125

ated upon, located above the forming-plug, and an adjustable support upon which said guide-head is adjustably mounted.

4. In a machine for making and shaping the necks of glass bottles, vials, &c., a base, an upwardly-extending guide-collar secured to the base, a supporting-rod having its lower end adjustably secured in said guide-collar, the said rod having a horizontal member at its upper end, a guide-head for supporting the body of the article operated upon, the said guide-head being adjustably held on the said horizontal member of the rod, and provided with upper and lower horizontal jaws, the jaws at the top and bottom being arranged in pairs, and a tool mounted for rotary motion and having shaping action upon the article.

5. In a machine for making and shaping the necks of glass bottles, vials, &c., a base, a shaft mounted to revolve in the base and carrying a forming-plug, shaping-jaws pivoted at opposite sides of the shaft and having heads at their upper ends arranged at opposite sides of the forming-plug and provided with shaping members, each of said jaws having on its inner face at the lower portion a longitudinal fin having a beveled inner edge, a cone revolvably and slidably mounted on the shaft, the said cone being provided with an annular groove, a hand-lever for forcing the cone upwardly between the lower beveled edges of the fins of said jaws to cause the shaping-

heads to move in direction of each other, the said lever having a spanner-arm provided with projections for engaging said groove in the cone, and a support for the article to be operated upon.

6. In a machine for making and shaping the necks of glass bottles, vials, &c., a vertical shaft mounted to rotate, means for driving the same, a forming-plug at the upper end of the shaft for application to the interior of the article to be operated upon, external shaping-jaws capable of movement toward and from each other, a block secured to the shaft and upon which the jaws are pivoted, means for controlling the movement of the jaws and comprising a member movable on the shaft below the said block, and a spring on the shaft between said movable member and the said block, a guide-head for the article to be operated upon located above the forming-plug, the said head being provided with upper and lower horizontal jaws, and a support on which said guide-head is adjustably mounted.

In testimony whereof we have signed our names to this specification in the presence of two subscribing witnesses.
